UNITED STATES PATENT OFFICE.

EMIL POMPLUM AND WALTER JENNERJAHN, OF CUDAHY, WISCONSIN, ASSIGNEES TO THE FISK RUBBER COMPANY, OF CHICOOPEE FALLS, MASSACHUSETTS, A CORPORATION OF MASSACHUSETTS.

ENGRAVING MACHINE.

Application filed July 31, 1924. Serial No. 729,312.

Our invention relates to machines for engraving designs on molds or similar articles and more particularly to a means for automatically positioning the article to be engraved so that the same arrangement or spacing of the component parts of the matter to be engraved may be repeated on a succession of articles in an accurate and expeditious manner. A further object is to provide means of this character which shall permit duplication of the article at a subsequent date without again laying out and spacing the matter to be engraved by actual measurements. With these and other objects in view our invention comprises the structure illustrated in the accompanying drawings, described in the following specification and specifically set forth in the appended claims, including such modifications thereof as will be obvious to those skilled in the art to which the invention appertains.

In the accompanying drawings

Figure 1 is a vertical section through a portion of an engraving machine, equipped with our invention,

Figure 2 is a plan view of the structure shown in Figure 1,

Figure 3 is a side elevation on an enlarged scale of the second cylinder of our device, and

Figure 4 is a section on the line 4-4 of Figure 2, also on an enlarged scale.

For the purpose of illustration we have shown our invention as applied to the cutting of brands or trademarks in tire molds, and in the drawings 1 designates the central post of a conventional mold engraving machine. A base member 2 mounted on post 1 rotatably supports a mold receiving table 3. Ball bearings 4 or other anti-friction devices may be inserted between the base 2 and table 3. Any suitable means may be provided for rotating the table. An arm 5 is secured at 6 to a bracket 7 fastened to the under side of base member 2 by bolts 8. Arm 5 is provided with bearings 10 and 11 which support a shaft 12 carrying at its inner end a bevel gear 14 which meshes with a ring gear 16 secured to table 3. Removably secured to the outer end of shaft 12 by nut 15 is a record cylinder 17 provided with a spiral groove 18. A split arm 20 is formed integral with bearing 10 and serves as a guide for a sliding

block 22 provided with a plunger 23 carrying a pin 24 adapted to ride in groove 18. The plunger 23 is urged toward the cylinder 17 by a spring 26, and is provided at its outer end with a head 28 by which it may be retracted.

As will be obvious shaft 12 and record cylinder 17 will rotate as table 3 carrying mold 30 rotates, and pin 24 will travel along the spiral groove 18, the block 22 sliding between guiding arms 20. The groove 18 is provided with recesses 32 in which pin 24 is adapted to seat under the influence of spring 26. These recesses correspond in position with the desired position of the letters or characters of the matter to be engraved in the mold such as is indicated at 34 in Figure 2. The cylinder therefore constitutes a record of the layout of the matter engraved and may be filed for future use.

The engraving tool indicated at 36 is operated from suitable patterns in any conventional manner and any suitable means may be provided for rotating table 3.

The operation is as follows. The proper record cylinder 17 is positioned on shaft 12 and secured by nut 15 and, with a mold positioned on table 3, pin 24 is started at the beginning of groove 18. The table 3 is then rotated until pin 24 drops into the first recess 32 arresting further movement of the table. The character represented by the recess is then engraved, pin 24 retracted by head 28, and the table 3 further rotated until again stopped by the pin engaging in the next recess when the mold will be positioned for the engraving of the next character. This operation is repeated until the complete design or mark is engraved. Preferably the recesses 32 are marked as shown in Figure 3 to visually indicate the character whose position they correspond to. The cylinder 17 may be changed for different sizes of molds or brandings and permits quick duplication of any engraving as required at any time. By our invention it is also possible to engrave all of the occurrences of a given letter (such as the E's for example) in succession, thereby avoiding changes of the pattern controlling the engraver 36. To accomplish this it is only necessary to hold pin 24 retracted until the recess indicating the desired character approaches when the pin is released to seat therein. As is obvious

the table 3 can be moved backward and forward at will, pin 24 correspondingly moving backward and forward in the groove 18 and always accurately positioning the mold by its engagement with the various recesses.

It will be understood that the specific form and application of our invention above described is illustrative only and that we are not limited thereto.

10 We claim:

1. In a machine for engraving articles a rotatable support, a spirally grooved cylinder, means to rotate the latter in synchronism with the movement of the support, there being recesses formed in the groove, and locking means co-operating with said recesses to releasably lock the support in predetermined engraving positions.
2. In a machine for engraving articles a rotatable support, a spirally grooved cylinder, means connecting the support and cylinder to rotate the latter in synchronism with the movement of the support, said groove having recesses formed therein and locking means co-operating with said recesses to releasably lock the support in predetermined engraving positions.
3. In a machine for engraving articles a rotatable support provided with a concentric gear, a shaft driven from said gear, and a record element releasably secured to said shaft adapted to control the positioning of

said support with respect to the engraving instrumentalities.

4. In a machine for engraving articles a 35 rotatable support provided at its periphery with a ring gear, a shaft driven from said gear, a spirally grooved cylinder releasably secured to said shaft, there being recesses 40 formed in said groove, a spring actuated pin mounted for longitudinal movement with respect to the cylinder traveling in said groove, and adapted to seat in the recesses to releasably lock the mold support in predetermined engraving positions.

5. A cylinder provided with a spiral 45 groove the effective length of which is proportioned to the length of a surface to be engraved there being indications along said groove corresponding in position to the desired positions of the engraving on such surface.

6. A cylinder provided with a spiral 50 groove the effective length of which is proportioned to the length of a surface to be engraved there being recesses formed in said groove corresponding in position to the desired position of the engraving on such surface.

In testimony whereof we have signed our 60 names to the above specifications.

EMIL POMPLUM,
WALTER JENNERJAHN.
